ATTORNEYS.

UNITED STATES PATENT OFFICE.

MAURICE D. SARBEY, OF CLEVELAND, OHIO, ASSIGNOR TO THE KEMET LABORATORIES CO. INC., A CORPORATION OF NEW YORK.

ELECTRIC VACUUM FURNACE.

Application filed December 1, 1925. Serial No. 72,550.

This invention relates to furnaces and more particularly to improvements in electrically heated vacuum furnaces.

In the construction of the vacuum furnaces heretofore built, it has been impossible to provide convenient access to the furnace chamber for the insertion and removal of the charge to be heated, and at the same time to readily make that chamber sufficiently 10 vacuum tight for use in furnacing operations requiring high vacua, or for use with oxidizable electrical resistors employed as a means of heating the furnace. Heretofore, conductors and pipes entering the furnace 15 chamber have also required separate gaskets and compressing means therefor, which demand constant attention to prevent leakage at these points. Furthermore, the furnace walls have been opaque, with merely a small 20 window providing a view of the inside of the chamber from only one point.

One of the principal objects of this invention is to provide a furnace which has a simple seal for retaining the highest vacua 25 that can be produced over mercury, which at the same time shall afford a simple means of access to the parts inside the furnace, and shall also provide a convenient means for leading into the furnace the required 30 size and type of electrical conductors to supply heating current to a resistor within the furnace, if the latter is to be so heated.

Other important objects of this invention are: to provide a heating resistor which 35 shall very rapidly reach the desired high temperature and with which the heating can be carried on in the absence of carbon or other vapors which might affect the charge; to provide expansion and contraction compensating means in the electrical circuit that 40 includes the resistor so that the latter may expand under heat without distortion; and to provide a transparent furnace wall through which the operation in the chamber 45 may be watched from various points.

The above and other objects and the novel 50 features of this invention will be apparent from the following description taken with the accompanying drawings, in which Fig. 1 schematically illustrates a vertical section of an electric vacuum furnace embodying this invention; and

Figs. 2 and 3 are detail sectional views

on the lines II—II and III—III of Fig. 1.

Referring to the drawings, the furnace 55 comprises a vacuum chamber V that has a wall W desirably in the form of a hollow transparent glass globe having a hollow stem W' at least 30 inches long. The tubular stem W', while preferably of transparent 60 glass integral with the globe, may be of metal, bakelite or other suitable material cemented to the globe, and is disposed in a substantially vertical position. The wall W, W' may be of any size and shape suited 65 to the operation for which it is to be used and to the material of which it is made. The furnace wall may be movably supported, as by suspending it in a shackle S that may be raised and lowered. 70

Normally the chamber V is liquid sealed, 75 preferably by means of mercury. The lower open end of the tube W' is disposed below the level of a body of mercury M in a reservoir R; while inside the hollow stem 80 W', but spaced from and desirably concentric with it, is a tube D, made of suitable insulating material such as glass or bakelite, which extends through a mercury tight joint in the bottom of the reservoir R and has 85 its lower end projecting below the level of a body of mercury M' in a reservoir R'. These two reservoirs constitute a stationary base for supporting the conductor and resistor assembly to be described, communicate with the atmosphere, and are of suitable 90 size to hold the quantities of mercury required for the mercury columns built up when high degrees of vacuum are created in the furnace chamber. 95

Air or other gases may be withdrawn from the chamber V to carry on operations under vacuum, and hydrogen, nitrogen, argon or other desired gases may be introduced into the same through a pipe H which, as shown, 95 extends through a mercury tight seal in the bottom of the reservoir R' and through the mercury M' and tube D into the chamber V, but may of course extend through either body of mercury and terminate at a suitable 100 height in the chamber V. To withdraw gas, the outer end of this pipe is connected to a suitable vacuum pump or other evacuating means.

The charge in the chamber V is desirably 105 electrically heated by means of a resistor T

which is connected in series circuit with electrical conductors C and K, which may be wire rods or tubes of metal or any material suited to the currents and temperatures to be used. If the resistor is to be operated at a temperature above the melting point of the conductor material, the conductors may be made as double or return tubes through which water or other cooling medium may be circulated. As shown, the conductor C may be in the form of an inverted U-shaped copper tube, the legs of which extend into opposite sides of the reservoir R through suitable mercury tight joints, thence up through the mercury M and the annular space between the walls W' and D, and into the chamber V, where they are connected by the bend C'. Similarly, the conductor K may be an inverted U-shaped copper tube, in a plane perpendicular to the conductor C, extending through mercury tight joints in the bottom of the reservoir R', thence up through the mercury M' and tube D into the chamber V, the bend K' at its upper end being disposed a distance below the bend C'. As shown, the conductors C and K, and the respective barometric columns of mercury through which they pass, are insulated from one another by the tube D. If desired, the lower ends of the conductors C and K may be bent under the lower edges of the stem W' and tube D, respectively, and brought up through the surfaces of the mercury seals M, M'. Furthermore, by suitably insulating the conductors C and K, the tube D as well as the mercury M' and reservoir R' may be dispensed with and all pipes and conductors brought out through the mercury seal M. Other supports may be used to carry the resistor assembly and hold the several parts in position, and wood or metal space blocks may be placed in both the tube D and the stem W' to reduce the quantity of mercury required for the columns. Positive and negative current supply cables 10 and 11 may be secured to the conductors C and K, respectively, by clamps 12 and 13; and suitable rubber hose or other means may also be coupled thereto for circulating cooling fluid therethrough.

The resistor T is adapted to carry the furnace charge and preferably consists of a refractory metal, such as tungsten, molybdenum or the like, and is desirably in the form of a container or cylinder formed by uniting two elongated curved sheets of tungsten, for example. The upper open end of the vertical tubular resistor is rigidly held and electrically connected to the conductor C by a copper casting B which may be split vertically into two similar sections and clamped to the legs of that conductor by bolts B'. The casting sections clamp the resistor against a thin steel ring N concentric with a hole L formed by opposed recesses in

the casting sections, thereby providing good electrical and mechanical connection between the resistor and the conductor C. The charge to be heated is placed inside the cylinder, access to which is obtained through the hole L. The bend C' is curved so as not to obstruct a view through the wall W endwise into the upper end of resistor to watch the charge. Since the interior of the heating element or resistor is practically completely enclosed, and is visible through the wall W, it can be sighted with an optical pyrometer, thereby obtaining true black body temperatures without correction.

A round steel block E fits into and closes the lower end of the resistor cylinder T, and the latter is clamped to the block E by the halves of a split steel ring F which are secured together by bolts F'. The resistor is thus in good electrical contact with the bottom block E, which carries two spaced copper switch blades J on its lower side to receive and make good sliding contact with a stationary copper block G that is electrically and mechanically secured to the top bend of the conductor K. As the resistor T heats up it expands considerably, which expansion and subsequent contraction are compensated for by the sliding connection between the blades J and the block G, thus avoiding damage to the resistor and other parts of the furnace. The casting B and ring N are kept cool by the circulation of cooling water through the conductor C; while the block G, blades J, ring F and block E are similarly cooled by the circulation of cooling water through the conductor K. With this cooling system, the furnace can be operated at any temperature up to the melting point of the tungsten or similar resistor, for such comparatively short lengths of time as it is usually desired to operate such a furnace, without damaging the terminals carrying the resistor and without distorting the latter.

To heat a charge to a high temperature under vacuum or sub-atmospheric pressure, the operation of the furnace is briefly as follows: Assuming that the exhaust pipe H is open to the outer air, the wall W, W' may be freely lifted off by the shackle S, exposing the resistor T. The material to be heated is then placed inside the resistor, and the wall W, W' is so replaced as to submerge the lower end of the stem W' in the mercury M, thereby sealing the chamber V since the tube D is already sealed by the mercury M'. The pipe H is then connected to the vacuum pumps to commence evacuating the chamber V. As the air is pumped out, the mercury rises in each of the tubes W' and D to the same height above their respective mercury reservoirs. As the air remaining in the furnace chamber approaches zero, the mercury in the two concentric tubes W', D approaches barometric

height, but since these tubes are over 30 inches long the mercury does not rise into the furnace chamber but remains approximately at a predetermined level, even with 5 the most nearly perfect vacua. The degree of vacuum can be readily estimated by the height of the mercury column in the stem W', for example, but of course it may be more accurately determined by the use of 10 gauges.

When the desired degree of vacuum has been reached, suitable electric current is supplied by closing a switch in circuit with cables 10, 11. The path of the current is as 15 follows: cable 10, conductor C, clamp B, resistor T, clamp E, block F, blades J, block G, conductor K and cable 11. At the end of the heating period, the current is shut off, 20 atmospheric pressure is restored in the chamber V and, when the concentric columns of mercury have dropped to their levels in the reservoirs, the globe or wall W, W' may be lifted off, giving quick and free access to the resistor and the charge therein.

25 The mercury makes an absolute seal around the opening of the furnace, as well as around the electrical conductors, exhaust pipe and other structural parts, and preserves without loss the vacuum or other desired pressure in the furnace chamber. Vacua can therefore be produced and held up to the capacity of the best vacuum pumping equipment, without the use of any troublesome joints, packings or ground glass 30 surfaces. By using water-cooled terminals for the resistor and providing expansion compensating means, operation of the improved furnace becomes very reliable and economical. By using a suitable resistor, 35 such as tungsten or molybdenum, very high temperatures can be very quickly attained, so that successive operations can follow each other very rapidly. Such temperatures are limited only by the melting point of the resistor, which in the case of tungsten is over 40 3000° C. The heating may be carried on in the absence of carbon or other vapors which might affect the charge, the temperatures reached being independent of the use 45 of any refractories since the furnace chamber is entirely free of these.

50 Any class of material may be heated in the furnace, irrespective of its electrical conductivity or the conductivity of a special container for it. The seal described may be used with any means of heating which can be used in a vacuum and is not limited to the use of the resistor and heating means described. The resistor described is not 55 limited to use in a vacuum but may be used in any type of furnace and in other suitable atmospheres. Various other changes may be made in the construction shown without departing from the principles of this invention or sacrificing any of its advantages.

I claim:

1. A furnace adapted for operations under high vacua comprising a furnace chamber having means therein for supporting a charge and means removable to afford access 70 to such charge-supporting means, a barometric liquid seal cooperating with such removable means to seal said chamber, and a conduit opening into said chamber.

2. An electrical furnace comprising a furnace chamber having therein means for supporting a charge, a conductor extending into said chamber to supply electric current to heat said charge, said chamber having a wall removable to afford access to such supporting means and charge; and mercury means 80 cooperating with said wall and said conductor to seal said chamber.

3. A furnace comprising a furnace chamber, barometric mercury sealing means for 85 said chamber, means for heating a charge in said chamber, and means whereby gas may be withdrawn from or introduced into said chamber.

4. A furnace as claimed in claim 3, wherein 90 said sealing means comprises concentric barometric columns of mercury.

5. An electric furnace comprising a furnace chamber, liquid sealing means for said chamber, electrical means for heating a 95 charge in said chamber, and means for conducting electric current through said liquid sealing means to such heating means in said chamber.

6. A furnace comprising a furnace chamber, liquid sealing means for said chamber, heating means within said chamber, means for supplying heating medium through said sealing means to said heating means, and means whereby gas may be withdrawn from 105 or introduced into said chamber.

7. An electric furnace comprising a furnace chamber, mercury sealing means therefore, electrical heating means within said chamber, means for conducting electric current through said sealing means to said heating means, and means whereby gas may be withdrawn from or introduced into said chamber.

8. An electric furnace as claimed in claim 110 115 7, wherein such conducting means comprises hollow tubing adapted for the circulation of cooling medium therethrough.

9. An electric furnace comprising a furnace chamber, liquid sealing means for said chamber, electrical means for heating a 120 charge in said chamber, and means whereby gas may be withdrawn from or introduced into said chamber through said sealing means.

10. An electric vacuum furnace comprising a furnace chamber, mercury means sealing said chamber, electrical heating means within said chamber, means for conducting electric heating current through said sealing means 125 130

to and from said heating means, and a conduit communicating with said chamber and extending through said sealing means.

11. A high temperature electric vacuum furnace comprising a furnace chamber; electric resistance heating means therein comprising a metal resistor adapted to carry the furnace charge; mercury means for sealing said chamber; and means for withdrawing gas from said chamber.

12. A high temperature electric furnace comprising a furnace chamber, liquid means for sealing said chamber, electrical heating means within said chamber, and means for 15 conducting electric current through such liquid sealing means to said heating means comprising means whereby such conducting and sealing means are adapted to be cooled.

13. An electric furnace comprising a furnace chamber, barometric columns of mercury sealing said chamber, a resistor in said chamber, electrical conductors extending through such mercury columns into said chamber and connected in circuit with said 20 resistor, and a gas conduit extending through one of said mercury columns into said chamber.

14. An electric furnace comprising a furnace chamber, electrical heating means entirely therein, electric current conducting means in circuit with said heating means, including relatively slidable contacts adapted to compensate for the expansion and contraction of such heating means, and barometric sealing means cooperating with said chamber and conductor to seal the furnace chamber.

15. A vacuum furnace comprising the combination of a base, a wall cooperating 40 with said base to provide a furnace chamber, liquid sealing means between said base and said wall, heating means disposed in said chamber at a greater height than the level of said sealing means when the gas is com-

pletely exhausted from said chamber, and means whereby gas may be exhausted from said chamber.

16. In an electric resistance furnace, the combination of a conductor and resistor assembly, supporting means for the same, a wall cooperating with said supporting means to provide a chamber enclosing said assembly, said wall being removable from said supporting means to afford access to said assembly, and a barometric sealing means 55 cooperating with said wall and said conductor.

17. A furnace adapted for operations under vacua comprising a furnace chamber having means therein for supporting a charge 60 and means removable to afford access to said charge supporting means, a barometric liquid seal comprising two columns of liquid with insulating means therebetween cooperating with such removable means to seal said chamber and a conduit opening into said chamber.

18. An electric furnace comprising an impervious tube open at one end and closed at the other to provide a furnace chamber 70 therein adjacent said closed end, a body of mercury cooperating with said open end to provide a barometric seal for said chamber, a resistor in said chamber, conductors electrically connected to opposite ends of said 75 resistor and means whereby one end of said resistor is free to expand relatively to the conductor connected thereto.

19. An electric furnace comprising a tubular wall of substantially uniform diameter 80 and of sufficient length to provide the height required for a barometric seal, said wall enclosing a furnace chamber, a resistor in said chamber, and mercury sealing means cooperating with said wall to seal said chamber.

In testimony whereof, I affix my signature.

MAURICE D. SARBEY.
